UNITED STATES PATENT OFFICE.

ROBERT EDWARD STEWART, OF DALLAS, TEXAS, ASSIGNOR TO HIMSELF AND JOHN HUGII SPIVEY, OF SAME PLACE.

SWITCH-STAND FOR DYNAMO-STATIONS.

SPECIFICATION forming part of Letters Patent No. 400,139, dated March 26, 1889.

Application filed December 28, 1888. Serial No. 294,855. (No model.)

To all whom it may concern:

Be it known that I, ROBERT EDWARD STEWART, of Dallas, in the county of Dallas and State of Texas, have invented a new and Improved Switch-Stand for Dynamo-Stations, of which the following is a specification, reference being had to the annexed drawings, forming a part thereof, in which—

Figure 1 is a front elevation of my improved switch-stand for dynamo-stations, and Fig. 2 is an end elevation.

Similar letters of reference indicate corresponding parts in both views.

The object of my invention is to provide a simple and efficient switch for introducing dynamos into an electric circuit and removing them therefrom, as occasion may require.

My invention consists in the combination, with outside circuit-wires, of switch-contacts arranged in pairs, there being as many pairs of such contacts as there are dynamos belonging to the circuit.

It also consists in the combination, with the pairs of contacts, of corresponding pairs of swinging arms, the arms of each pair being insulated from each other and adapted to engage the contacts of the outside circuit.

It also further consists in the combination, with the contacts and the swinging arms, of a hinged plate connected with each pair of swinging arms, all as will be hereinafter more fully described.

The frame A, forming the support of the switch, consists of the side bars, $a a'$, the end bars, $b b'$, and the longitudinal bars $c c'$, attached to the face of the end bars, $b b'$. To the frame A (in the present case) are secured four switches, $B B' B'' B'''$; but I do not limit or confine myself to any particular number, and as the four switches are precisely alike a description of the details of one will be sufficient.

To the bar c are attached spring-contacts d , each being provided with two spring-arms, e . To the inner face of the bar a are attached two angled plates, f , which are oppositely arranged with reference to each other, and which are connected with the binding-posts $g g'$, placed upon the outer side of the bar a . To the plates f are pivoted the arms h , the said arms

being connected with each other by wooden bars $i j$, placed between them and fastened to the arms by screws or bolts. The arms h are arranged exactly opposite the spaces between the spring-arms e , and are provided with ears k , which may be forced between the arms e , forming a frictional contact.

To the inner surface of the bar c is pivoted a right-angled plate, l , which is capable of being turned over the top of the said bar c and forming an electrical connection with the contacts d . The plate l , near the center of its free edge, is provided with ears m , between which is pivoted one end of a connecting-rod, n , the opposite end of which is pivotally connected with the wooden bar j . To the lower end of the bar c is attached a binding-post, o , and in like manner to the lower end of the bar c' is attached a binding-post, o' . A wire, p , connects the binding-post o with the first contact d of the switch B' . The second contact d of the said switch is connected by a wire, q , with the first contact d of the switch B , the second contact of the said switch being connected by the wire r with the switch B'' , and the said switch B'' is connected in turn with the switch B''' by the wire s . The switch B''' is connected with the binding-post o' by the wire t . A dynamo is connected with each pair of binding-posts $g g'$. The binding-posts $o o'$ are connected with the outside circuit-wires. When the arms $h h$ are thrown into engagement with the spring-arms e , the current from the dynamo passes through the arms h into the circuit through the contacts d . When it is desired to throw the dynamo out of the circuit, the arms h are withdrawn from between the spring-arms e . This operation breaks the circuit of the dynamo and carries the angled plate l over so that it touches both of the contacts d , as shown in the switch B' , the circuit being completed through the said angled plate l .

My improved switch is designed more particularly for introducing a reserved dynamo into the circuit when one of the dynamos in use becomes disabled. In such case the reserved dynamo would be connected with an open switch, and when the dynamo is to be introduced onto the circuit the arms h are

swung over into engagement with the spring-arms *e*, and at the same time the hinged angled plate *l* is removed from the contacts *d*, thereby causing the current to flow from the dynamo 5 through the said arms *h* into the circuit. At the same moment the switch of the disabled dynamo is removed from the circuit by an operation which is the reverse of that just described.

10 By the use of my improved switch all danger of shocks to the attendant is avoided, as the operation of introducing a dynamo into the circuit or removing it therefrom is performed by the movement of a single switch, 15 the switch being provided with a non-conducting handle of sufficient length to prevent the possibility of the flowing of the current to the person of the operator.

Having thus described my invention, I claim 20 as new and desire to secure by Letters Patent—

1. In a switch-stand, the combination, with a pair of electrical contacts and a pair of swinging arms insulated from each other and adapted to be moved together to engage the 25 contacts, of a movable plate connected with the swinging arms and fitted to touch both electrical contacts, substantially as specified.

2. In a switch-stand, the combination of interrupted outside circuit-conductors provided with spring-contacts on opposite sides of the 30 breaks of the circuit, one or more pairs of arms, each pair being connected with the terminals of a dynamo, and plates arranged to close the circuit between the contacts, substantially as specified. 35

3. In a switch-stand, the combination of the frame *A*, contacts *d*, attached to the frame, arms *h*, adapted to engage the contacts, the plates *l*, and the rods *n*, substantially as specified. 40

4. In a switch-stand, the combination of the frame *A*, the spring-contacts *d*, attached to the frame, the angle-plates *f*, the arms *h*, provided with ears *k*, the insulating-bars *i j*, connecting the said arms *h*, the hinged angled plates *l*, the connecting-rods *n*, and the circuit-connections, substantially as specified. 45

ROBERT EDWARD STEWART.
